UNITED STATES PATENT OFFICE.

JAMES HOWDEN HUME, OF GLASGOW, SCOTLAND.

MEANS FOR CONTROLLING THE AIR-SUPPLY TO LOCOMOTIVE-BOILER FURNACES.

1,028,881.

Specification of Letters Patent. Patented June 11, 1912.

Application filed December 14, 1909. Serial No. 533,089.

To all whom it may concern:

Be it known that I, JAMES HOWDEN HUME, a subject of the King of the United Kingdom of Great Britain and Ireland, and 5 residing at Glasgow, Scotland, have invented a certain new and useful Improved Means for Controlling the Air-Supply to Locomotive-Boiler Furnaces, of which the following is a specification.

- 10 In locomotive boiler furnaces worked under forced draft, as in Howden's forced draft system, provision must be made for closing the air inlet valves while the furnace door is open for firing the furnace in order 15 to obviate risk of injury to the firemen by blowing back of the flames, and for that purpose interlocking devices are employed to insure that the inlet valves shall be closed before the door can be opened. As in such 20 furnaces the firing operation must be frequently repeated, and the firing door is open for relatively long periods, the advantage of the forced draft system is thus in large measure lost. To overcome that objection 25 and provide means whereby enhanced draft, over natural draft, may be maintained at all times even during firing operations, we apply to locomotive boiler furnaces an arrangement comprising the combination with 30 interconnected devices for controlling the forced and induced drafts of means herein-after described for at the same time controlling the fire door.

The invention is illustrated in the accompanying drawings in which—

- Figure 1 is a part longitudinal elevation, part vertical section on the line $x-x$, Fig. 2, and Fig. 2 is an end elevation, of a locomotive boiler provided with the improved 40 means for controlling the air supply to the furnace; Figs. 3, 4 and 5 are details showing the forced draft and auxiliary air inlet valves in various positions; Fig. 6 is a vertical section through the middle of the furnace door and through the forced draft supply trunk; Fig. 7 is a vertical section at right angles to Fig. 7 of the furnace door casing; Fig. 8 is a detail view of the valve for controlling the induced draft and Fig. 45 9 is a diagram showing the connections between the valves for controlling the induced draft and forced draft, and the relative positions of said valves.

Referring to the drawings, forced draft 50 air is led to the furnace as from a fan a , Fig. 1, which may be located at the front of

the boiler through a trunk A and branch trunks A¹, and is admitted to the furnace beneath the grate by means of a valve A², shown more particularly in Figs. 6 and 9, 60 adapted to be operated in known manner as by means of a lever D and other devices hereinafter referred to.

The interlocking means for preventing opening of the furnace door B comprise a 65 guard C attached to the operating lever D, said guard being arranged to extend, *e. g.* in front of the door latch E. The lever D is connected by means of a link F to a lever arm G of a cock or valve H on a steam pipe, 70 which, when the cock or valve is open, as shown in Fig. 8, supplies steam from the boiler by means of a pipe I to an induced draft jet device J. The valve levers are so arranged and connected that when the valve 75 A² is opened to admit the forced draft air supply, the steam supply valve H is closed, as shown in Fig. 9, and vice versa. As shown in Figs. 1 and 2, the valve A² is 80 closed, and when in this position the door latch E can be raised clear of the guard C, thus permitting the furnace door to be opened.

In order to permit of regulating the volume of air to be supplied through the trunks 85 M¹, valves K operated by hand levers L are fitted in said trunks. To provide for a supply of air to the underside of the fire grate N, when the furnace door B is open and the induced draft system is in operation, the 90 usual auxiliary valve means for admitting air at atmospheric pressure are fitted at the base of the fire box and connected to the devices controlling the forced draft air inlet valve A² and steam cock H. In express 95 locomotives which are driven mainly with the boiler at the forward end, a single auxiliary air admission valve may be provided at the forward end only; but for locomotives which are used for short journeys and which often run with the tender in front, a plurality of air admission openings are preferably provided at each end, as shown, and are adapted to be closed by means of valves 100 O and P, which valves are secured to spindles O¹, P¹, respectively, and are coupled by a lever O² secured to said spindle O¹, one arm of a bell crank lever P² secured to said spindle P¹, and by a connecting link M, so 105 that to suit the direction of running (indicated by the arrow R), when the valves O at one end are opened, the valves P at the 110

other end are closed, as indicated in Figs. 1, 4 and 5, or vice versa, as indicated in Fig. 3. The said valves are preferably operated by means of an independent hand lever S, 5 a link S¹, and the other arm of said bell crank lever P². Valves U and V are interconnected by means of levers U¹, V¹, and a link Q, and are adapted to be controlled by means of the lever D so as to close said 10 auxiliary valve openings, when the forced draft system is in operation, as indicated in Fig. 5; said valve or valves being preferably operated by means of a rod F¹ connected by a pin d on the lever D to a lever arm T 15 which is secured to the spindle of the valve A².

As shown particularly in Figs. 8 and 9, the casing of the furnace door is made hollow and is adapted by means of a branch 20 trunk a¹ to communicate with the forced draft air which may thus enter the furnace by way of a manually-operated valve a² and by perforations a³ in said casing, said valve being opened slightly to permit air to enter 25 through the furnace door opening just sufficient to prevent blowing back of smoke or the like when the furnace door is opened.

Having now described my invention what I claim and desire to secure by Letters Patent of the United States is:—

1. In a locomotive boiler furnace having a fire door, in combination, a valve controlling

a forced draft to said furnace, a valve controlling an induced draft to said furnace, a guard for locking the fire door, an operating lever connected to said guard, and links connecting said lever with said valves, whereby when said guard is in position to lock the fire door the forced draft is in operation, and when said guard is in unlocking position the induced draft is in operation.

2. In a locomotive boiler furnace having a fire door, and a fire box with openings below the same, in combination, a valve controlling a forced draft to said furnace, a valve controlling an induced draft to said furnace, a guard for locking the fire door, an operating lever connected to said guard, links connecting both said valves with said guard whereby when said guard is in position to lock the fire door the forced draft is in operation, and when said guard is in unlocking position the induced draft is in operation, valves controlling the said openings in the fire-box and links connecting said valves with said lever.

In testimony whereof I have signed my name to this specification in the presence of two subscribing witnesses.

JAMES HOWDEN HUME.
